UNITED STATES PATENT OFFICE.

JAMES A. ALLARDICE, OF ROME, NEW YORK, ASSIGNOR TO HATHORN & COMPANY, OF SARATOGA SPRINGS, NEW YORK, A FIRM.

FILLING APPARATUS.

SPECIFICATION forming part of Letters Patent No. 769,244, dated September 6, 1904.

Application filed June 29, 1903. Serial No. 163,492. (No model.)

To all whom it may concern:

Be it known that I, JAMES A. ALLARDICE, a citizen of the United States of America, and a resident of Rome, county of Oneida, State of New York, have invented certain new and useful Improvements in Filling Apparatus, of which the following is a specification, reference being had to the accompanying drawings, forming a part thereof.

10 My invention relates to filling apparatus such as are employed for filling bottles, kegs, barrels, &c., and particularly to means for bottling liquids impregnated with gas, such as are known as "sparkling" liquids.

15 My invention consists in means for expelling air from receptacles to be filled by the substitution of gas therefor of the same nature as the gas with which the liquid is impregnated, preferably taken from the same source

20 of supply, in then bottling the liquid impregnated with the gas under receiver-pressure and without exposing the same to the air, in hermetically sealing the receptacle by corking same, and in carrying out all the 25 foregoing operations in a single power-machine operated through various controlling-levers by a single operator.

The main object of my invention is to bottle liquids of this character under pressure in 30 receptacles from which the air has been entirely excluded and to seal same after the bottling process before removal from the machine in order to prevent access of air thereto.

35 My invention further consists in certain novel details of construction and combination of parts, as hereinafter more fully set forth, and other advantages will appear hereinafter.

I will now proceed to describe an apparatus 40 embodying my invention and will then point out the novel features in claims.

In the drawings, Figure 1 is a front view of an apparatus embodying my invention, Fig. 2 is a detail view in central vertical

45 transverse section of the upper power-cylinders and the upper cross-head, showing the gas and water valve in transverse section and showing also a portion of one of the filling-

spindles. Fig. 3 is a view, partially in front and partially in transverse section, of the lower power-cylinder, the drip-table, and the bottle-carrier. Fig. 4 is a detail vertical transverse view, the plane of section being taken substantially upon the line 4-4 of Fig. 1. Fig. 5 is a detail view in horizontal section, taken substantially upon the plane of the line 5-5 of Fig. 1. Fig. 6 is a view in vertical longitudinal section of the parts shown in Fig. 5, the plane of section being substantially upon the line 6-6 in such figure.

The class of work for which my apparatus is particularly adapted is the bottling of water impregnated with gas received under pressure from a natural spring, and in the present application I have illustrated the bottling-machine so connected.

In the following description I will describe my apparatus as adapted for the filling of bottles, though it will be apparent that it might be adapted for filling receptacles of other kinds as well, and for convenience in description I will term the apparatus a "bottling-machine" and will term the operation which it performs a "bottling operation" without thereby intending to restrict the use of the machine to the filling of bottles only.

In the drawings a receiver 1 is illustrated, which is connected by pipe 2 with a suitable source of supply, such as a natural spring. The spring delivering water impregnated with gas and free gas under pressure will constantly supply the receiver. A valve 3 may be employed to regulate or close the supply as may be desired. A water-overflow pipe 4 leads from about the middle of the receiver, so that while the lower part of the receiver will contain water impregnated with gas the upper part of the receiver will contain gas alone. A gage-glass 5 may conveniently be employed to show the water-line and a pressure-gage 6 to denote the pressure in the receiver.

The bottling-machine comprises a base-plate 7, two standards 8, and a transverse head 9. The base 7 supports a power-cylinder 10, in which is arranged a suitable piston, and a

plunger having a piston or plunger rod 11 rises upward therefrom and supports at its upper end a bottle-carrier 12. The bottle-carrier 12 is arranged to carry two bottles 5 (see particularly Fig. 3) and is preferably connected to the said piston-rod 11 by means of a pintle 13, so that a slight swinging movement is permitted to compensate for slight variations in the length of the bottles. Set- 10 screws 14 limit the amount of movement permitted to the said bottle-carrier.

The piston-rod 11 carries a clamp 15, which is securely bolted thereto and which may be adjusted to a correct position along the piston- 15 rod 11, so as to limit the downward movement of the said piston-rod in accordance with what length bottle it is desired to employ. A stud 16, secured to the head of the cylinder 10 or some other stationary portion, engages 20 the said clamp 15 and prevents rotation of the piston-rod 11, while permitting full reciprocation.

Motive fluid is admitted to the lower end of the cylinder 10 through a branch pipe 17 25 to force the piston therein and bottle-carrier carried thereby upwardly. Return movement is effected by gravity upon closing admission of the motive fluid and exhausting same from the cylinder. The piston-rod 11 30 passes through and is guided by a hub or boss arranged in the center of a drip-table 18, secured to the standards 8. The drip-table 18 is arranged to catch any overflow or drippings and is provided with a waste-pipe 19 35 for conveying same away.

A central table or support 20 is rigidly secured to the standards 8 and acts as a support for filling-heads 21 and a transverse operating-cylinder 22. Another transverse operating-cylinder 45 is arranged in a line with the cylinder 22 and is secured to one of the standards 8. The filling-heads 21, as shown more particularly in Figs. 4, 5, and 6, comprise each a casing 23, the lower end of which terminates in a receiving-neck for the upper end of a bottle, having a washer 24 for coacting with the mouth of the bottle and effecting a tight joint at such point. The upper end of the casing is provided with a gland and stuffing-box 25, through which the reciprocating filling-spindle is permitted to pass. The gland and stuffing-box 25 is in a direct line with the receiving-mouth of the casing, so that when the filling-spindle 26 is moved downward it 55 may enter the bottle freely. The upper end of the casing is also provided with a transverse bore, to which is fitted a plug-valve 27, and with an air-vent 28, a gas-discharge 29, and a passage 30, leading to the interior of 60 the casing. The valve-plug 27 has cross ports or passages which in one position of the valve open the interior of the casing to the gas-discharge, in another position of the valve open the interior of the casing to the air-

vent and close the gas-discharge, and in a 65 position intermediate the two said positions close both the air-vent and the gas-discharge.

By referring to Figs. 4 and 5 it will be seen that there are two filling-heads 21, arranged in a line with the two bottles adapted to be 70 carried by the bottle-carrier 12. It will be understood that the two heads being similar the foregoing description of one will apply equally to the other. In a direction at right angles to a line passing through the stuffing- 75 box 25 and the receiving-neck for the bottle the casings 23 are each provided with a hollow bore 31, terminating in an outwardly-flaring head or circular boss 32. A cork-trough 33, fitted to the bore 31, is formed as an extension of a cap or head 34, with which each of the said filling-heads is provided. The caps or heads 34 are rigidly secured to a cross-head 35, bolted to a piston-rod 36, connected to a piston 37, mounted in the cylinder 22. The 80 cork-troughs 33 are open-topped, so that corks may be dropped into same by hand prior to each operation of the machine. The cylinder 22 is provided with a branch admission-pipe 38 for admitting motive fluid to the front end 90 thereof, and upon admission of such motive fluid the cross-head 35 will be drawn toward the left, thereby closing the interior of the casings 23 by engagement of the caps or covers 34 with the circular bosses 32, packing- 95 rings 39 being carried by the said caps or covers to effect tight joints. A spring 40 is arranged for returning the parts to the positions shown in the drawings upon the exhaust of motive fluid from the cylinder 22. 100

The foregoing movement of the parts to close the casings 23 by means of the caps or covers 34 will have the effect only of carrying the corks into the casing, but will not carry them into a line with the bottle-necks, nor will it effect the necessary compression of the corks, and for these latter purposes I provide plungers 41, secured to a cross-head 42, connected by means of a piston-rod 43 with a piston 44, mounted in the cylinder 45. The inner ends of the plungers 41 are provided with heads 46, arranged within the cork-troughs 33. The plungers 41 pass through stuffing-boxes 47 in the cross-head 35 and are permitted to move freely therethrough, while such stuffing-boxes prevent leakage from or to within the casings. A branch pipe 48 leads from the source of motive fluid to the rear of the cylinder 45, whereby motive fluid may be admitted behind the piston 44 to drive the 110 plungers 41 forward. When this is effected, the corks within the casing will be pushed forward to the rear walls of the casing 23, which are curved to complement the curved portions of the heads 46, the said plungers 115 and casing rear walls thus forming pressing means for the corks, which are thereby compressed in a line with the neck of the bottles, 120 125

so that they may after such compression be directly inserted. Weights 49 are connected by cords 50 to the cross-head 42, passing over pulleys 51, in order to give the necessary 5 change in direction. These weights tend to return the plungers 41 and piston 44 to the position shown in Fig. 5 of the drawings after an operation of the device as just described.

It will be noted that when the cross-head 10 35 is drawn to the left by the movement of the piston 37 to close the casings 23 the plungers 41 and the piston 44 will be drawn forward therewith a like distance. Subsequent 15 operation of the plungers 41 is permitted, however, by reason of the fact that the stroke permitted by the cylinder 45 is considerably longer than that permitted by the cylinder 22, the plungers 41 sliding through the cross-head 35 in the manner just explained during 20 such movement.

The above-mentioned filling-spindles 26, of which there are two, are secured at their upper ends to the cross-head 52, arranged to vertically reciprocate and mounted upon guide- 25 ways 53 upon the standards 8. The said cross-head is secured to a piston-rod 54, connected with a piston 55, mounted in one of the upper cylinders 56. A branch pipe 57 for conveying motive fluid to the said cylinder 56 is connected with the lower end of said cylinder, so that motive fluid when admitted to said cylinder maintains the piston 55, cross-head 52, and filling-spindles 26 in their uppermost 30 position. Exhaust of motive fluid from the cylinder 56 will permit the parts to fall by gravity and will cause the filling-spindles 26 to enter the bottles, all for a reason to be presently explained. Two valve-casings 58 are carried by the cross-head 52 and are bored 35 out to receive valve-plugs 59, having suitable cross-over ports arranged to register with certain ports in their respective casings. Each of the said valve-casings has a water-admission port or passage 60, a gas-admission port or passage 61, and a port or passage 62, leading to the interior of its respective filling-spindle 26. When the valve-plugs are turned 40 in one direction, such being the direction in which one of them is shown in Fig. 2, the water-admission passages are open through the valve-plugs to the filling-spindles 26. By turning the valve-plugs through an arc of 45 ninety degrees the water admission is closed and admission is opened from the gas-admission passage 61 to the filling-spindles. In intermediate positions of the said valve-plugs both of said passages 60 and 61 are closed.

The two valve-plugs 59 are connected together by a coupling 63, and in like manner 50 the valve-plugs 27 in the casings 23 are also connected together. The valve-plugs 59 and 27 are provided with miter gear-wheels 64, the miter gear-wheel 64 of the plugs 27 meshing with a corresponding miter gear-wheel 65,

rigidly secured to an operating-spindle 66, 65 and the miter gear-wheel 64 upon the plugs 59 meshing with a miter gear-wheel 67, secured to a sleeve 68, slidably mounted upon the spindle 66, but arranged to rotate therewith. The sleeve 68 is further mounted in a 70 bearing 69, carried by the cross-head 52, so that the proper engagement between the miter-gears 64 and 67 will be maintained while the cross-head 52 is moved down or up, and in any position of the latter operation of the 75 spindle 66 will cause synchronous operation of the valve 59 and the valve 27. A handle 70 is secured to the lower end of the spindle 66 for the purpose of operating same.

The initial position of the filling-spindles 26 80 is a raised one, in which the lower end of the said spindles is above the interior of the main portion of the casing 23, as shown clearly in Fig. 6, and in which the piston 55 is at the top of its cylinder, as shown in Fig. 2. During the operation of expelling air from the bottles and filling the bottles with liquid the spindles 26 are permitted to enter the bottles, and for this purpose motive fluid is exhausted 85 from the cylinder 56, whereby the said spindles move downward by gravity for the above purpose. After the bottles are filled the spindles are withdrawn to the position shown in the drawings, and the corks are moved into position beneath the said spindles and in a 90 line with the bottles. The spindles are then used as corking-plungers for the purpose of forcing the corks into the necks of the bottles, and for so operating the said spindles I employ a power-cylinder 71, which is secured to the upper head 9, which head further forms a closure for the upper end of said cylinder. A piston 72 is mounted in said cylinder, and a piston-rod 73, carried by the said piston, extends downwardly to engage the upper end 95 of the piston 55 in the cylinder 56. The stroke permitted the piston 72 in the cylinder 71 is much shorter than the stroke permitted the piston 55 in the cylinder 56 and, in fact, is just sufficient to move the spindles 26 such 100 a distance only as to properly insert the corks in the bottles. The diameter of the cylinder 71 is greater than the diameter of the cylinder 56, and hence although motive fluid may be admitted to the cylinder 56 at the same 105 time as motive fluid is admitted to the cylinder 71 above the piston 72 the greater energy imparted to the piston 72, due to its greater superficial area, will overcome the resistance 110 of the piston 55, and both will move downward. When motive fluid is exhausted from the upper end of the cylinder 71, admission of 115 motive fluid to the cylinder 56 will return the parts to their normal positions, in which they are shown in the drawings. A branch pipe 120 74 connects with the upper end of the cylinder 71 for the purpose of admitting motive fluid thereto.

The various branch pipes 17, 38, 48, 57, and 74, leading, respectively, to the power-cylinders 10, 22, 45, 56, and 71, all connect with a main supply 75 for compressed motive fluid 5 under pressure, which may conveniently be compressed air. A single operating-valve 76 controls the branch pipes 17 and 38, one valve being sufficient for both branches for the reason that the cylinders 10 and 22 will have motive fluid admitted thereto and exhausted therefrom at the same time. An operating-valve 77 controls the branch 48, leading to the cylinder 45, and similar operating-valves 78 and 79, respectively, control the branch pipes 57 and 74. The said controlling-valves are all similar, and it will therefore be necessary to describe but one. One of these controlling-valves—namely, valve 78—is shown in transverse section in Fig. 6, and therein it will be seen that said valve is a three-way valve, in one position being arranged to admit motive fluid from the main to the branch pipe, and in the other position being arranged to cut off admission from the main pipe and connect the branch pipe with exhaust to atmosphere through a port or passage 80, as shown in such figure.

Each branch pipe is provided with a regulating-cock 81 and a by-pass, in which is arranged a check-valve 82, closing in the direction of admission and opening in the direction of exhaust. By this arrangement the controlling-valves may be opened to their fullest extent without any attempt at regulation, while admission at the correct speed will be insured by proper regulation of the regulating-valves 81. When the cylinders are exhausting, however, a full and open exhaust will be insured through the by-passes in which the check-valves 82 are arranged, such by-passes and check-valves being of such capacity as to permit unobstructed discharge.

In connecting the bottling-machine with the receiver 1 a pipe 83, which leads from the lower end of the said receiver 1, is connected to the water-inlets 60 of the valve-casings 58, and a pipe 84, which leads from the upper end of the said receiver, is connected to the gas-inlets 61 of the casings 58 and to the gas-discharges 29 of the casings 23. Controlling-valves 85 and 86 are arranged in the pipes 83 and 84, and a regulating-cock 87 is preferably arranged in that branch of the pipe 84 leading to the gas-inlets in the casings 58.

The initial condition of the bottling-machines is with the operating-valves 76, 77, and 78 closed to admission and open to exhaust and with the operating-valve 79 closed to exhaust and open to admission. The controlling-handle 70 is at this time in its intermediate position, so that the valve-plugs 59 and 27 are in their dead positions, with all the ports controlled thereby closed.

During normal operation the valves 85 and

86, controlling flow of gas and water from 65 the receiver 1, may be open, for the reason that the said valve-plugs 27 and 29, controlled by the operating-handle 70, will operate to control supply of fluid therethrough.

A complete cycle of operation of the apparatus is then as follows: Two empty bottles are placed upon the bottle-carrier 12, which at this time is in its lowest position, and two corks are dropped into the cork-troughs 33, at this time in their rearward positions, as shown more particularly in Figs. 5 and 6. Operating-valve 76 is now turned, so as to close exhaust and admit motive fluid to the cylinders 10 and 22. The result of this will be to lift the bottle-carrier 12 and to press the bottles firmly up against the washers 24, carried by the casings 23, and to close the interior of the casings 23 by drawing the caps or covers 34 into position against the circular heads or bosses 32. The next operation is to turn the operating-valve 79, so as to exhaust motive fluid from the cylinder 56 and to permit the cross-head 52 and parts carried thereby to descend. This will cause the spindles 26 to descend into the bottles. The controlling-lever 70 may then be turned to such a position as to admit gas through the gas-admission passages 61 and valve-plugs 59 to the filling-spindles and to permit air to be discharged through the valve-plugs 27 and air-discharge vents 28. Gas from the receiver 1 will thus be admitted to the bottles, at the lower ends thereof, and will force out air from the bottles through the upper end. When air from the bottles has been entirely replaced by gas, the operating-handle 70 may be returned to its intermediate position, so as to cut off further admission of gas, and at the same time prevent return of air. The next step is to turn the operating-handle to its opposite position, so as to admit water from the receiver, through the filling-spindles, to the bottle, and to open the passages to gas-discharge through valve-plugs 27, whereby water will be allowed to descend into the bottles by gravity and displace gas, which will return into the top of the receiver. It will be noted that at this time there is a balance of pressure between the bottle and the receiver both as to gas and water, as the lower part of the bottle is in connection with the lower part of the receiver, and the upper part of the bottle is in connection with the upper part thereof. When the operating-handle 70 is turned to admit water to the bottles, the operating-valve 79 should also be turned to admit motive fluid to the lower end of the cylinder 56, so as to gradually raise the filling-spindles. When the filling-spindles have been raised to their highest positions and the bottles have been filled substantially full with water, the operating-handle 70 will be returned to its intermediate position, thereby

cutting off supply of water and communication with gas-discharge. The next step is to turn the operating-valve 77, so as to admit air to the cylinder 45 to force the corks into line 5 with the bottles and the operating-spindles and to compress same between the rear walls of the casings 23 and the plunger-heads 46. The following step is to turn the operating-valve 78, so as to admit air to the upper end of the cylinder 71 to force the operating-spindles 26 down a distance sufficient to force the corks into the neck of the bottles, so as to hermetically seal the bottles, and the final step is to return the operating-valves 78, 77, and 76 to 15 their normal release positions, whereby the operating-spindles will be again lifted to their uppermost positions, the plungers 46 withdrawn, the caps or covers 34 removed to open the casings 23, and the bottle-carrier 12 permitted to descend, so as to free the bottles 20 from engagement with the said casings and permit their removal. Drippings from the casings 23 will be caught by the drip-table 18 and will pass thence through the pipe 19 to 25 waste.

It will be seen that by the employment of my apparatus I am enabled to completely expel air from the bottles by displacing same with gas with which the water to be bottled 30 is impregnated, to fill the bottles only in the presence of such gas, and finally to hermetically seal the bottles.

It will also be seen that the apparatus for carrying the foregoing into effect is a simple 35 one and may be readily, simply, and quickly operated, the operation of the entire machine being effected by the mere operation of certain operating and controlling valves.

It will be obvious that the foregoing is but 40 one embodiment of my invention and that the same is capable of many and varied modifications within the spirit and scope of my invention, and, further, that certain parts may be employed in connection with other parts of 45 different construction. Hence I do not desire to be limited only to the precise details of construction and combination of parts herein.

What I claim is—

1. In a filling apparatus, the combination 50 with a filling-head adapted for connection to the mouth of a receptacle to be filled, a filling-spindle adapted to pass through said filling-head and to enter said receptacle, and means for inserting a stopper into said filling-head, 55 of means for depressing said filling-spindle to cause the same to pass through the said filling-head and enter said receptacle, and separate means for depressing said filling-spindle a limited distance only for the purpose of forcing the stopper into the mouth of said receptacle.

2. In a filling apparatus, the combination 60 with a filling-head having an opening adapted for connection to the mouth of a receptacle to

be filled, a filling-spindle adapted to pass 65 through said filling-head and enter said receptacle, and means for inserting a stopper into said filling-head, of two fluid-pressure-actuated devices of different stroke arranged to operate said filling-spindle, one adapted for 70 raising and lowering said spindle the full distance of its stroke, the other adapted for forcing downward said spindle a shorter distance only, for the purpose of forcing a stopper driven by said spindle into the mouth of said 75 receptacle.

3. In a filling apparatus, the combination with a filling-head having an opening adapted for connection to the mouth of a receptacle to be filled, a filling-spindle adapted to pass 80 through said filling-head and to enter said receptacle, and means for inserting a stopper into said filling-head, of two fluid-pressure cylinders of different strokes and pistons and piston-rods therefor, and means for admitting 85 fluid under pressure thereto, the piston of longer stroke connected to said filling-spindle and arranged to raise and lower the same, the piston of shorter stroke acting upon the other piston and arranged to force said filling-spindle 90 downward for the purpose of forcing a stopper driven by said spindle into the mouth of said receptacle.

4. In a filling apparatus, the combination with a filling-head having an opening adapted 95 for connection to the mouth of a receptacle to be filled, a filling-spindle adapted to pass through said filling-head and to enter said receptacle, and means for inserting a stopper into said filling-head, of two fluid-pressure 100 cylinders of different stroke and different diameters arranged tandem, and pistons therefor, the piston of the cylinder having the longer stroke and the smaller diameter connected to said filling-spindle and arranged to 105 raise and lower the same, the piston of the other cylinder arranged to act upon said smaller piston and adapted to force said filling-spindle downward for the purpose of forcing a stopper driven by said spindle into the 110 mouth of said receptacle.

5. In a filling apparatus, the combination with a filling-head adapted for connection to the mouth of a receptacle to be filled, and having a cork-receiving chamber adapted to receive and hold a cork out of line with the mouth of the receptacle, said chamber normally closed but having a side opening for receiving a stopper, of means for closing said side opening, independent means for forcing 120 said stopper through the interior of the filling-head into line with the mouth of the receptacle, and means for forcing said stopper into the mouth of said receptacle.

6. In a filling apparatus, the combination 125 with a filling-head adapted for connection to the mouth of a receptacle to be filled, and having a cork-receiving chamber adapted to re-

- ceive and hold a cork out of line with the mouth of the receptacle, said chamber normally closed but having a side opening for receiving a cork or stopper, of a cap or cover 5 for closing such side opening, independent means for forcing a stopper introduced through such opening, through such chamber, into line with the mouth of the receptacle while such opening is closed by said cover, 10 and means for forcing said stopper into the mouth of said receptacle.
7. In a filling apparatus, the combination with a filling-head comprising a casing 28 having an opening in its lower end adapted for 15 connection to the mouth of a receptacle to be filled, and having a stuffing-box 25 at its upper end opposite the said opening, and having also a transverse bore 31, of a cap or cover 34 for closing the bore 31, a plunger 46 for moving 20 the stopper into position, a spindle 26 for inserting the stopper into the bottle, and means for operating the cover, the plunger and the spindle.
8. In a filling apparatus, the combination 25 with a filling-head having a receiving-opening at its lower end adapted for connection to the mouth of a receptacle to be filled, a stuffing-box at its upper end for receiving the lower end of the filling-spindle, and a transverse bore 30 for receiving a stopper-trough, of a stopper-trough arranged to receive a stopper, and mounted to reciprocate in said transverse bore, means for reciprocating same, a stopper-plunger arranged within said stopper-trough, and 35 means, other than said means for reciprocating the stopper-trough for reciprocating said plunger.
9. In a filling apparatus, the combination 40 with a filling-head adapted for connection to the mouth of a receptacle to be filled, and a filling-spindle adapted to pass through said filling-head and to enter said receptacle, of means for supplying liquid under pressure and separate means supplying gas under pressure, both connected to said filling-spindle, 45 and a valve in connection with said filling-head, having air and gas vents, the latter connected with said means for supplying gas under pressure, whereby the pressure in the 50 source of gas-supply and in the receptacle may be balanced during the filling, and the liquid caused to flow in by gravity.
10. In a filling apparatus, the combination 55 with a filling-head adapted for connection to the mouth of a receptacle to be filled, and a filling-spindle adapted to pass through said filling-head and to enter said receptacle, of means for supplying liquid under pressure and separate means for supplying gas under 60 pressure, and a valve arranged to permit successive flow of gas and liquid therefrom to said spindle, and a valve in connection with said filling-head, having air and gas vents, the latter connected with said means for supply-
- ing gas under pressure, whereby the pressure 65 in the source of gas-supply and in the receptacle may be balanced during the filling, and the liquid caused to flow in by gravity.
11. In a filling apparatus, the combination 70 with a filling-head and a valve arranged therein, of a filling-spindle arranged to reciprocate through said filling-head, a valve arranged to control admission to said filling-spindle, and means for synchronously operating the two said valves.
12. In a filling apparatus, the combination 75 with a filling-head, a portion of which comprises a valve-casing having two discharge-passages, and a valve mounted in said casing arranged to connect one or other of said discharge-passages with the interior of said filling-head in accordance with its position, of a filling-spindle arranged to reciprocate through said filling-head, a valve-casing to which said filling-spindle is secured, said valve-casing 80 having two inlet-passages, a valve mounted in said casing and arranged to connect one or other of said inlet-passages with the interior of said filling-spindle in accordance with its position, and means for operating the said 85 valves.
13. In a filling apparatus, the combination 90 with a filling-head, a portion of which comprises a valve-casing having two discharge-passages, and a valve mounted in said casing 95 arranged to connect one or other of said discharge-passages with the interior of said filling-head in accordance with its position, of a filling-spindle arranged to reciprocate through said filling-head, a valve-casing to which said filling-spindle is secured, said valve-casing 100 having two inlet-passages, a valve mounted in said casing and arranged to connect one or other of said inlet-passages with the interior of said filling-spindle in accordance with its 105 position, and means for synchronously operating the said valves.
14. In a filling apparatus, the combination 110 with a filling-head, and a discharge-controlling valve mounted therein, of a vertically-reciprocating inlet-valve, a filling-spindle secured to said inlet-valve and arranged to enter said filling-head, and a single operating-handle 115 70 operatively connected with both said valves.
15. In a filling apparatus, the combination 120 with a filling-head, a bottle-carrier, stopper-inserting means, and a filling-spindle, of means for operating same comprising power-cylinders, branch pipes leading from a source of 125 motor-fluid supply connected to said power-cylinders, operating-valves for said branch pipes, regulating-cocks between said operating-valves and said cylinders, by-passes around said regulating-cocks, and check-valves in said by-passes, opening in a direction away from said cylinders.
16. In a filling apparatus, the combination

with a receiver, of a filling-head having a discharge-passage connecting with the upper end of the said receiver and having an air-discharge, a valve therefor, a supply-valve casing having two receiving-passages, one connecting with the lower end of said receiver, and the other with the upper end thereof, a valve fitted to said casing controlling said supply-passages, a filling-spindle connected

to said supply-valve casing, and means for operating said valve.

Signed at Rome, New York, this 13th day of June, 1903.

JAMES A. ALLARDICE.
